UNITED STATES PATENT OFFICE.

FREDRICK L. KOLLEBERG, OF CHICAGO, ILLINOIS.

MACHINE FOR FLANGING STEAM-BOILER HEADS.

SPECIFICATION forming part of Letters Patent No. 317,145, dated May 5, 1885.

Application filed October 10, 1884. (No model.)

To all whom it may concern:

Be it known that I, FREDRICK LEONARD KOLLEBERG, of Chicago, in the county of Cook and State of Illinois, have invented certain new and useful Improvements in Machines for Flanging Steam-Boiler Heads; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Heretofore when heads of steam-boilers were being flanged it was necessary, after being cut in the form of a circular plate heated to a white heat and placed on the bed-plate preparatory to being flanged, to find the center thereof before commencing the flanging operation. This frequently causes a delay during which the plate cools and has to be reheated. After the center of the head-plate is found a hole has to be driven through it for the insertion of a pivotal pin, around which the plate is revolved by contact with the flanging-rollers as the bed-plate of the machine is gradually brought from a horizontal to a vertical position. The pivotal hole thus made in the head-plate is liable to weaken the same, although it is afterward plugged with a rivet; and, moreover, its location frequently inconveniences the boiler-maker when making holes therein for the insertion of the boiler-flues.

The object of my invention is to supply means for centering the plate on the bed-plate of the machine, which avoids the necessity for perforating the same, and means for advancing the bed-plate to or withdrawing it from the flanging-rollers, whereby the machine may be adapted for flanging heads of a greater or less diameter; and it consists in radially-adjustable dogs operating in radial slots in the bed-plate, a screw-shaft for advancing or withdrawing the bed-plate, substantially as hereinafter more fully explained, and as illustrated in the drawings, in which—

Figure 1 is a side elevation of my machine. Fig. 2 is an end view thereof. Fig. 3 is a plan view of the bed-plate. Fig. 4 is a vertical longitudinal section of the bed-plate. Fig. 5 is a detail view. Figs. 6 and 7 are detail views showing the bearings of the roller-shafts.

In the drawings, A represents a rectangular open frame having pivotal studs *a* projecting laterally from the inner corners thereof nearest the flanging-rollers, which are journaled in suitable bearings in the ends of the horizontal arms of the vertical inverted-L-shaped frames B. These frames B are connected by a horizontal cross-frame, B', upon which the side bars of the rectangular frame A rest when the same is in a horizontal position. Resting on this rectangular frame A is the bed-plate C, having a central circular boss, C', extending downward from its under surface, and having a central pivoting-pin, *c*, seated in said boss, the head of which projects above the upper surface of said plate C, and is serrated, so as to hold a head-plate firmly when it is centered and pressed downward thereon.

Pivoted in and between suitable lugs projecting upward from one side of the said bed-plate and extending laterally over the same in such position as to pass immediately over said pivoting-pin *c* is a clamping-bar, D. The end of this bar D opposite to where it is pivoted is slotted or bifurcated, and is clamped down to hold a head-plate while the same is being flanged by means of an oscillating screw, D', pivoted to the contiguous side of the bed-plate, which can be swung upwardly between the arms of the bifurcated end of said bar D, and by means of a suitable nut hold the said bar down.

Pivoted in and extending downward from the under surface of the bar D, immediately over and in alignment with pin *c*, is a likepin, *d*, the bearing-surface of which is similarly serrated. When the head-plate of the boiler has been entered by the means to be herein-after described, it is placed between these two pins, its center being in vertical alignment with the pivotal centers of the said pins.

In order to center the head-plate—that is, make its center coincide with those of the pivoting-pins *c* and *d*—I make in the bed-plate the slots *e e e e*, radiating in different directions from the pivotal center of the pin *c*. Adjustable radially in these slots are the dogs *E*, having a shoulder or tooth extending above the bed-plate, so that they will as they advance at an equal rate in said slots push the said plate until its center corresponds to that of pin *c*.

These dogs have bosses, to which the shoulders above referred to are connected by a neck, which are tapped longitudinally and engaged by the screws F, the inner ends of which are journaled in the boss C' of the bed-plate, and the outer ends in suitable hangers depending from the under surface of the plate C. These screws all have pinions f near their inner bearings which mesh with and are driven by the large 10 beveled gear G, journaled on the boss C', as shown, in alignment with pins c and d; and the gear G is driven by one of the screws F, which has its outer end, F', extended through its outer bearing and an elongated horizontal 15 slot in the rectangular frame A, where a crank can be slipped over it and the same thereby operated.

Journalled in a suitable frame, H, at right angles to the pivotal line of the bed-plate C 20 and contiguous to the inner edge is the drive-shaft I, having on the end adjacent to said plate C the flanging-roller i, the uppermost point of the periphery of which is on a plane just above that of the upper surface of the said 25 bed-plate. The inner end of the drive-shaft is journaled in a journal-box in the frame J, and on its extremity beyond this frame J is placed a large gear or pulley, by means of which motion is imparted to it.

30 That portion of the frames H and J above the bearings of the shaft I is divided into two vertical arms, between which are placed the vertically-adjustable journal-boxes H' and J', in which is journaled the shaft K. This shaft 35 K is arranged parallel with and in the same vertical plane as shaft I, and it has on its end nearest the bed-plate a flanging-roller, k, similar in every respect to roller i on the contiguous end of said shaft I. It is between these 40 two rollers i and k that the edge of the heated and circular head-plate is placed preparatory to being flanged. The shaft K between its bearings is provided with a pinion, k', which meshes with and derives motion from a similar gear, i', on the drive-shaft I.

The upper portion of the frame H, between the arms of which the journal-box H' is vertically adjustable, describes a segment of a circle struck from the journal-box J', which 50 latter has that portion in which the journal of the said shaft K rests swiveled, so that the end of the shaft having thereon the roller k may be oscillated vertically by means of the lever L, pivoted at one end between the arms m m, 55 extending obliquely upward from the frame H and being connected to said journal-box H' by a pitman or link, n.

It will be observed that in order to flange head-plates of various diameters, and in order 60 that the circumferential edges of the same when properly centered may come between the flanging-rollers i and k, the centering-pins c and d will have to be advanced toward or withdrawn from the said rollers, according as 65 the diameter of the head-plate may require. To do this I have journaled in the end pieces of the rectangular frame a screw, N, running

longitudinally and centrally between the sides of said frame A, and having its outer end extend beyond its bearings and adapted to receive the boss of a suitable crank by which it is turned. This screw passes through boss C' of the bed-plate, which is tapped to receive the same, and according as the screw is turned to the right or left the bed-plate is advanced 70 or withdrawn from the flanging-rollers. 75

In order that the plate C may not as it advances interfere with the flanging-rollers it is cut away at n', as shown in the drawings.

The bed-plate being very heavy cannot ordinarily be lifted by hand. For this purpose, therefore, a derrick or other hoisting device may be used, which may, as preferred, be operated by hand or steam power. I do not, however, lay particular claim to the bed-plate- 80 elevating devices; nor do I wish to be understood as claiming invention for the means for applying power to the roller, as various ways 85 may be adopted.

In operation my invention operates substantially as follows: The plate is cut to the required diameter, then placed in a furnace and heated to a white heat, and then placed on the bed-plate and centered by the centering devices. The clamping-bar is then swung 90 downward and secured by the screw and nut thereon, as described, after which the bed-plate is advanced to or withdrawn from the flanging-rollers until the edges of the head-plate are properly between the said rollers. Power 95 is then applied to the drive-shaft, and as the rollers revolve and turn the head-plate the bed-plate upon which the latter is centered is gradually lifted from a horizontal to a perpendicular position, thus flanging the said head-plate. After the head-plate has been flanged 100 and the bed-plate is being swung to its normal position, the lever L is manipulated to lift the journal-box in which is journaled the end of the shaft K, carrying roller k, so that the 105 flanged portion of the head-plate may escape from between the said flanging-rollers without being injured. The head-plate is then 110 removed and the machine is ready for another operation.

What I claim as new, and desire to secure by Letters Patent, is—

1. The combination, with a vertically-oscillating bed-plate having slots therein radiating from the center thereof, of the dogs adjustable radially in said slots, as hereinbefore set forth.

2. In a steam-boiler-head-flanging machine, the combination of the bed-plate, the radially-adjustable dogs moving in slots radiating from the center of said bed-plate, and the clamping-bar, as set forth.

3. In a boiler-head-flanging machine, the combination, with a vertically-oscillating bed-plate, radially-adjustable dogs moving in slots 120 in said bed-plate and radiating from the center thereof, and a clamping-bar running laterally and centrally over said plate, of the flanging-rollers.

4. In a boiler-head-flanging machine, the combination, with a vertically-oscillating bed-plate, radially-adjustable dogs, and a clamping-bar, of the flanging-rollers, the upper one of which can be oscillated, substantially as and for the purpose set forth.

5. The combination, in a boiler-head-flanging machine, with the horizontally-revolving bed-plate having a circular boss extending to downward from the center thereof, of a screw journaled in the end pieces of the rectangular

frame supporting the bed-plate and passing longitudinally and centrally through the boss of said bed-plate, which is tapped suitably to receive the same.

In testimony that I claim the foregoing as my own I hereunto affix my signature in presence of two witnesses.

FREDRICK L. KOLLBERG.
